UNITED STATES PATENT OFFICE.

HENRY F. HAYDEN, OF WASHINGTON, DISTRICT OF COLUMBIA, ASSIGNOR
TO THE INTERNATIONAL VAPOR FUEL AND CARBON IRON AND MANU-
FACTURING COMPANY, OF SAME PLACE.

APPARATUS FOR GENERATING VAPOR FROM LIQUID HYDROCARBONS.

SPECIFICATION forming part of Letters Patent No. 278,793, dated June 5, 1883.

Application filed June 11, 1881. Renewed March 26, 1883. (No model.)

To all whom it may concern:

Be it known that I, HENRY F. HAYDEN, a citizen of the United States of America, residing at Washington, in the District of Columbia, have invented certain new and useful Improvements in Apparatus for Generating Vapor from Liquid Hydrocarbons; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to that class of vapor-generators in which steam is used for causing the vaporization of liquid hydrocarbons; and the nature thereof consists in certain improvements in the construction of the same, herein-
20 after shown and described.

It also consists in certain improvements in the construction of furnaces in which vapor fuel is burned.

In the accompanying drawings, Figure 1 is a vertical section of the apparatus. Fig. 2 illustrates in detail the arrangement of the superheating-pipes.

In the drawings, A designates the furnace, from whence the products of combustion pass upward to the smoke-pipe T.

B is the steam-superheater, which consists of a number of communicating coils of pipe arranged the one above the other. One of these coils is represented in plan in Fig. 2.

35 C is a valve for regulating the flow of superheated steam from the superheater to the retort or generator G.

D is the oil-supply valve.

E is the pipe through which the superheated steam enters the generator.

F is the pipe through which the liquid hydrocarbon enters the generator.

H is the pipe which conducts the vapor from the generator.

45 I is a valve for regulating the flow of vapor to the point where it is consumed.

J is a receiver for residuum, provided with a valve, K, through which the residuum may be drawn off.

50 L is a tank in which the hydrocarbon is held

at a required pressure by means of a loaded valve, R.

N is a perforated plate for supplying air to the burner M.

O is the combustion-chamber.

P is the pump by which the liquid hydrocarbon is forced upward from the tank Q.

The operation of the apparatus is as follows: The superheater B and the generator or retort G are heated to the degree required for the vaporization of the liquid hydrocarbon by the heated gases which rise from the furnace A. Free steam is admitted to the superheater B, from whence it passes to the generator G, its flow being regulated by the valve C. The liquid hydrocarbon is introduced into the said generator immediately below the point at which the steam enters through the pipe F, and is vaporized by the action of the steam. The retort G is slightly inclined, so that if any of the 70 heavier hydrocarbons are not vaporized they will flow into the receiver J, located at the side of the casing of the apparatus, from whence they may be drawn off through the valve K. It will thus be seen that this arrangement of 75 the generator G and the receiver J will prevent the hydrocarbons which have not been vaporized from lodging in the retort G or being carried away through the pipe H. It is also to be observed that the receiver J, being outside of 80 the casing, is not subjected to the heat imparted by the escaping products of combustion.

The flow of vapor to the burner M is regulated by the valve I. The burner M, which consists of a perforated pipe, is supplied with air heated 85 to about 500° in its passage through the flue Y, arranged on top of the furnace X by means of the curvaluna perforated plate N. By this arrangement the heated air is thoroughly intermixed with the vapor entering through the 90 perforations in the burner M and carried forward to the combustion-chamber, which consists of a number of pillars, Z, of refractory material, arranged within the mixing-chambers of the furnace. The burner and furnace in 95 which the gas is burned are not claimed in this application, as they will form the subject-matter of another application for Letters Patent of the United States. The tank L is supplied with liquid hydrocarbon by means of the pump 100

P, connected with the reservoir Q, the pressure in the tank being regulated by the loaded valve R, which may be set at a pressure of twenty pounds to the square inch. The surface 5 plus hydrocarbon is returned to the tank Q, from whence it was taken by a pipe communicating therewith. The residuum removed from the receivers J through the valve K may be mixed with coal or other fuel used in the furnace.

It will thus be seen that by the apparatus the lighter hydrocarbons may be continuously vaporized and the heavier hydrocarbons continuously drawn off and used as fuel.

Having thus described my invention, I claim and desire to secure by Letters Patent of the United States—

1. In the described apparatus for vaporizing

liquid hydrocarbons, an inclined generator arranged above the superheating-pipes, and provided with a vertical receiver arranged on the outside of the casing of the apparatus. 20

2. The combination of the superheater B, the steam-supply pipe E, the inclined generator G, and the hydrocarbon-supply pipe F, as 25 and for the purposes described.

3. The combination of the generator G, the hydrocarbon-supply pipe F, the tank L, pump P, and loaded valve R, as and for the purposes described. 30

In testimony whereof I affix my signature in presence of two witnesses.

HENRY F. HAYDEN.
